United States Patent Office

Des. 183,855
Patented Nov. 4, 1958

183,855

FAN OR SIMILAR ARTICLE

Walter E. Moore, Trumbull, and Robert J. Reading, Stratford, Conn., assignors to General Electric Company, a corporation of New York

Application July 22, 1957, Serial No. 47,021

Term of patent 14 years

(Cl. D26—7)

Fig. 1

FIG. 2.

FIG. 3.

Fig. 1 is a front perspective view of a fan or similar article embodying our new design;

Fig. 2 is a front elevational view of the fan shown in Fig. 1 with a portion at the center being broken away; and

Fig. 3 is a fragmentary cross-sectional view of a portion of the fan shown in Fig. 1.

It is to be understood that the radial wires in Figs. 2 and 3 are uniformly spaced around the complete circumference of the coaxial rings of the fan guard as shown in Fig. 1.

The dominant features of our new design are shown in solid lines in the drawing. The broken line showing

of a mounting panel and opening therein is for illustrative purposes only.

We claim:

The ornamental design for a fan or similar article, substantially as shown and described.
